The ornamental design for a vehicle, as shown and described.

DESCRIPTION

FIG. 1 is a front and right side perspective view of a vehicle showing my new design;

FIG. 2 is a rear and left side perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

Any elements shown in broken lines form no part of the claimed invention but instead show environmental aspects thereof. The broken lines adjacent to a shaded portion form an unclaimed boundary of the design.
